CLAIM

The ornamental design for a remote control, as shown and described.

DESCRIPTION

FIG. 1 is a perspective view of a remote control showing my new design;

FIG. 2 is a perspective view viewed from another angle thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the area "9" shown in FIG. 1. The broken lines depict portions of the remote control that form no part of the claimed design. The dot-dash broken lines indicate where the enlargements have been taken, and form no part of the claimed design.

1 Claim, 9 Drawing Sheets
